US0D1112604S

(12) **United States Design Patent** (10) **Patent No.:** **US D1,112,604 S**
Wood et al. (45) **Date of Patent:** **** Feb. 10, 2026**

(54) **POOL FILTER CLOSURE REMOVAL DEVICE**

(71) Applicant: **Wood's Pool Service**, Acworth, GA (US)

(72) Inventors: **Jeffery Wood**, Acworth, GA (US); **Katy Maddox**, Acworth, GA (US)

(73) Assignee: **Wood's Pool Service**, Acworth, GA (US)

(**) Term: **15 Years**

(21) Appl. No.: **29/934,712**

(22) Filed: **Mar. 27, 2024**

(51) **LOC (15) Cl.** **08-05**

(52) **U.S. Cl.**

USPC **D8/21**; D23/209

(58) **Field of Classification Search**

(57) **CLAIM**

An ornamental design for a pool filter closure removal device as shown and described.

DESCRIPTION

FIG. 1 is a front perspective view of a pool filter closure removal device showing the claimed design;

FIG. 2 is a top view thereof;

FIG. 3 is a bottom view thereof;

FIG. 4 is a front view thereof;

FIG. 5 is a back view thereof;

FIG. 6 is a right side view thereof; and,

FIG. 7 is a left side view thereof.

1 Claim, 4 Drawing Sheets
